TIRE

Claude A. Hart, Walsall, England, assignor to The Dunlop Company Limited, Erdington, Birmingham, England, a British company

Filed May 16, 1969, Ser. No. 17,182

Claims priority, application Great Britain Nov. 29, 1968

Term of patent 14 years

Int. Cl. D12—14

U.S. Cl. D90—20

FIG. 1

FIG. 2

FIG. 3

FIG. 4

FIG. 1 is a perspective view of the tire of my new design,

FIG. 2 is a fragmentary perspective view,

FIG. 3 is a fragmentary plan view,

FIG. 4 is a cross sectional view of the tire of this invention.

Although only a portion of the design has been shown in FIG. 1, it should be understood that the tread pattern is continuous over the circumference of the tire.

I claim:

The ornamental design for a tire, as shown and described.
